United States Patent Office.

EDWARD HULBERT, WILLIAM F. STEELE, AND HENRY C. DAY, OF GLOVERSVILLE, NEW YORK.

Design No. 4,143, dated June 7, 1870.

DESIGN FOR THUMBS OF GLOVES.

The Schedule referred to in these Letters Patent and making part of the same

To all whom it may concern:

Be it known that we, EDWARD HULBERT, WILLIAM F. STEELE, and HENRY C. DAY, all of Gloversville, in the county of Fulton and State of New York, have invented and produced a new and original Design for the Thumbs of Gloves and Mittens, of which the following is a specification.

The nature of our design is fully represented in figs. 3 and 4 of the accompanying drawing, to which reference is made, and in which—

Figure 1 represents a front view of a glove, with our new design for thumb applied.

Figure 2, a similar view before attaching the thumb.

Figures 3 and 4 represent views, on a larger scale, of the design for the inner and back pieces of which the thumb is made.

The thumb-hole A, in the body of the glove or mitten, is of rounded form at its outer end, and of a double angular shape, as formed by a pointed projection, a, at its inner end, as clearly shown in fig. 2, which serves to illustrate the mode of applying our new design for the thumb-pieces.

The thumb is made in two pieces, B and B', which are afterward sewn together, forming a seam on both or opposite sides of the thumb.

The one piece, B, which constitutes the back of the thumb, is of the configuration shown in fig. 3, being rounded at its larger end, to correspond with the rounded shape of the thumb-hole at its outer end, to which it is applied.

The other piece, B', which constitutes the inner portion of the thumb, is of a spread V-shape at its larger end, to receive within it the point a of the thumb-hole.

A thumb thus made is neater and better fitting; the stock may be cut closer in making it; the back B, which is exposed to but little wear, be made of lighter leather or material than the inner portion B', which is exposed to much wear, and the glove or mitten be made cheaper.

We claim the design for the thumb of a glove or mitten, as herein represented and described.

EDWARD HULBERT.

WM. F. STEELE.

H. C. DAY.
